UNITED STATES PATENT OFFICE

HERBERT R. CAMPBELL, OF PATERSON, NEW JERSEY

BRIDGE WARNING INDICATOR

Application filed August 7, 1928, Serial No. 298,121. Renewed February 18, 1930.

This invention relates to bridge warning indicators.

Indicators of this kind have been commonly placed at the entrances of railroads and the like to bridges, tunnels and other places where head room over the cars is so limited as to make it dangerous for a person on top of the car to remain erect. Such warnings or indicators commonly employ a series of flexible cords or other elements which give notice of the approach of a train to the obstruction by striking the person on the car so that he may either get off the top of the car or lie flat thereon and thus escape being struck.

As usually constructed if one of these tell-tales becomes broken or detached from its support or if the tell-tales become entangled it is necessary to erect a ladder to make the repairs required and thus, for a time, the track is obstructed and the workmen are in danger.

The principal object of the present invention is to provide a device of this kind where-in, in the event of repairs or replacements being necessary, the entire series of tell-tales may be removed without the necessity of a workman approaching on the track or being placed in any danger from being struck by a passing train.

A second important object of the invention is to provide an improved structure of this kind so arranged that the removal of one set of tell-tales may be used to effect the placing in position of a second set so that at no time is the bridge, tunnel or other structure left unguarded.

With the above and other objects in view as will be hereinafter apparent, the invention consists in general of certain novel features of construction and combinations of parts hereinafter fully described, illustrated in the accompanying drawings and specifically claimed.

In the accompanying drawings like characters of reference indicate like parts in the several views, and:

Figure 1 is a front elevation of one form of the invention showing it in position across a track or railroad.

Figure 2 is a detail view illustrating a second form of the invention.

Figure 3 is an enlarged detail view partly in section showing one end of the second form.

Figure 4 is a section on the line 4—4 of 55 Figure 3.

Figure 5 is an enlarged section on the line 5—5 of Figure 1.

Figure 6 is an enlarged section on the line 6—6 of Figure 1. 60

In the present embodiment of the invention it will be seen that the device is shown supported on a pair of poles 10 seated in suitable foundations 11 at opposite sides of the railroad tracks T, it being understood that the 65 device may be readily modified to stretch across any number of tracks from one up and that it is not confined to a double track road as here shown. Also it will be noted that in some instances, as where the approach to a 70 tunnel is between retaining walls, the posts may be omitted and the device carried directly by such retaining walls. It is not however, deemed necessary to show all such modifications as may be made. In the present construction a supporting wire or cable 12 is

stretched between the tops of the poles 10 and depending from this cable are hangers 13 which carry supporting means 14. Said supporting means are preferably in the form of a 75 housing or tubular supporting member having both ends open as shown the bore forming a guideway and from end to end of the underside of said tubular member there is provided a slot 15. The tubular member may either be straight throughout as shown in Figure 2 or it may have its ends curved downward as shown in Figure 1 at 16 so that they may be secured to the poles 10 by clamps 17. Preferably through this tubular member extends 80 tell-tale carrying means such as the flexible tell-tale carrier 18 which is here shown in the form of a suitable rope, the rope being of course large enough so that it will not fall through the slot 15. This rope has its ends 85 projecting from the opposite ends of the member 14 and these ends are detachably secured to the posts by means of clips 19 so that the rope is thereby kept from slipping through 90 the support. Extending transversely through 95

the carrying means or carrier 18 are the upper ends of tell-tale pins 20 which are held in position by suitable nuts 21, the said pins being of wire or rod. The tell-tales proper 20 are attached to the lower ends of the pins 20 and, 5 may be of cord although light wires may be used throughout. The tell-tale pins depend through the slot 15 and together with the tell-tales proper 20 are slidable with the carrier 18 and are normally grouped over the tracks 10 T as clearly shown in Figure 1.

With the invention as thus constructed it is obvious that all of the tell-tales and the carrier may be removed as a unit from the tubular supporting member 14 by loosening the 15 ends of the carrier rope and drawing on one end. At the same time a new set may be placed in position by attaching a second carrier rope and its set of tell-tales to the remaining end of the first carrier so that when one 20 carrier and its tell-tales are drawn out the other carrier and its tell-tales will be brought into position. Thus for no appreciable time will the bridge, tunnel or other structure be 25 left unguarded.

There has thus been provided a simple and efficient device of the kind described and for the purpose specified.

Although the forms herein illustrated and 30 described are believed to represent the device in its preferred construction, changes of detail can be made, as for instance, the supporting member 14 may be made sufficiently strong to support the various parts without the use 35 of the cable 12 and hangers 13.

It is also obvious that other minor changes 40 may be made in the form and construction of the invention without departing from the material spirit thereof. It is not, therefore desired to confine the invention to the exact form herein shown and described, but it is desired to include all such as properly come within the scope claimed.

Having thus described the invention, what 45 is claimed as new, is:

1. In a bridge warning indicator, supporting means including a fixed substantially horizontal housing extending across the railroad track, a tell-tale carrier directly supported by and slideable lengthwise on said fixed housing, and tell-tales depending from and slideable with said carrier.

2. In a bridge warning indicator, supporting means including a fixed housing extending 55 across the railroad track and having a longitudinal guideway, a tell-tale carrier carried by said fixed housing and slideable lengthwise in said guideway, and tell-tales depending from and slideable with said carrier.

3. In a bridge warning indicator, a fixed supporting member extending across the railroad track and having a longitudinal chamber, a longitudinal slot on its underside extending the length of said chamber, a tell-tale

carrier slideable in said chamber, tell-tale pins passed transversely into said carrier extending through and slideable in said slot, and tell-tales depending from said tell-tale pins.

4. In a bridge warning indicator, a tubular supporting member having a slot on its under side, a flexible tell-tale carrier slideable in said supporting member, tell-tales depending from said carrier through said slot, and means for releasably securing the carrier in 70 adjusted position in the supporting member.

5. In a bridge warning indicator, a tubular supporting member open at both ends and having a slot extending from end to end along its underside, a flexible tell-tale carrier mounted in the supporting member for sliding movement longitudinally therethrough, said carrier having its ends projecting from the ends of said supporting member, and tell-tales depending from said carrier through said slot.

6. In a bridge warning indicator, a tubular supporting member open at both ends and having a slot extending from end to end along its underside, flexible tell-tale carrying means mounted in the supporting member for sliding movement longitudinally therethrough, said means having ends projecting from the ends of said supporting member, tell-tales depending from said means through said slot, and means for releasably securing the projecting ends of said carrying means.

7. In a bridge warning indicator, a tubular supporting member open at both ends and having a slot extending from end to end along its underside, flexible tell-tale carrying means mounted in the supporting member for sliding movement longitudinally therethrough, said means having ends projecting from the ends of said supporting member, said member having ends curved downwardly for attachment to supports at the sides of a track, and tell-tales depending from the part of the carrying means between said curved ends and extending downwardly through the slot.

8. In a bridge warning indicator, a tubular supporting member open at both ends and having a slot extending from end to end along its underside, flexible tell-tale carrying means mounted in the supporting member for sliding movement longitudinally therethrough, said means having ends projecting from the ends of said supporting member, said member having ends curved downwardly for attachment to supports at the sides of a track, tell-tales depending from the part of the carrying means between the curved ends thereof and extending downwardly through said slot, and means for releasably securing the projecting ends of said carrying means.

9. In a bridge warning indicator, a pair of spaced posts arranged at the sides of a railroad, a hanger wire stretched between the

upper ends of said posts, a tubular supporting member suspended from said hanger wire from one post to the other and having both ends open and a slot extending from end to end of its underside, a flexible tell-tale carrier mounted in the supporting member for sliding movement longitudinally therethrough, said carrier having its ends projecting from the ends of the supporting member, tell-tales depending from the carrier through said slot, and clamps detachably securing the ends of the carrier to said posts.

Signed at Paterson, in the county of Passaic, and State of New Jersey, this 14th day of July, 1928.
